UNITED STATES PATENT OFFICE.

DELAVAL W. HOUSE, OF CHICAGO, ILLINOIS.

WIRE-PULLER OR COME-ALONG.

1,036,626.

Specification of Letters Patent. Patented Aug. 27, 1912.

Application filed April 17, 1911. Serial No. 621,543.

To all whom it may concern:

Be it known that I, DELAVAN W. House, a citizen of the United States, and a resident of the city of Chicago, in the county 5 of Cook and State of Illinois, have invented certain new and useful Improvements in Wire-Pullers or Come-Alongs; and I do hereby declare that the following is a full, clear, and exact description of the same, reference being had to the accompanying drawings, and to the numbers of reference marked thereon, which form a part of this specification.

This invention relates to improvements in 15 that class of wire pullers used by electricians and others in drawing wires through a conduit or for stretching wire wherever required.

The object of the invention is to afford 20 an exceedingly simple and strong device, capable of being adjusted to different sizes of wire or steel tape and so constructed as to firmly grip and engage the wire without injuring the same.

It is also an object of the invention to 25 afford a construction capable of permitting the operator using both hands in pulling and also to afford a construction in which any suitable grappling means may be engaged to the come-along to apply power thereto, if desired.

In the preferred form of my invention shown in the drawings: Figure 1 is a plan view of a device embodying my invention, 35 showing the same in use. Fig. 2 is a section thereof on line 2—2 of Fig. 1. Fig. 3 is a section on line 3—3 of Fig. 1. Fig. 4 is a section on line 4—4 of Fig. 1. Fig. 5 is a section on line 5—5 of Fig. 1.

As shown in the drawings: The body or 40 base plate of the puller comprises a metallic plate 1, of any suitable material, conveniently cast or forged metal, which, as shown, is relatively broad at its rear end and tapers 45 forwardly to a relatively narrow neck 2, which connects integrally with the transverse handle 3, which, as shown, is convexly curved on its forward side and extends equal distances on each side of its connection with the 50 base plate. Said ends of the handle are flanged on opposite sides along the rear edge to afford a broad bearing for the hand of the operator, said flanges 4, being milled on their outer or convex faces to prevent slipping of the hands. An aperture 5, is provided through the handle at its center to en-

gage any pulling tackle therewith. The rear end of the base plate is also flanged, said flanges 6, as shown in Fig. 4, being also milled on the outer side to afford better engagement with the hand. Parallel transverse flanges or ribs 7 and 8, are provided on one face of said base plate and fitting closely therebetween and riveted to the base plate is a hardened steel block 9, the inner 60 face of which is substantially in alinement with the slot or notch 16 through the flange 6, at the rear end of the base plate, as shown in Fig. 1. Integrally connected with the base plate and slightly at the rear of said block 9, and directed with the axis thereof toward the center of said block, is a sleeve 10, which, as shown, is slotted transversely, as is also the base plate, to receive through said sleeve and co-axially therewith, the 65 milled nut 11, through which is engaged a threaded shank 12, which at its inner end directed toward the block 9, is provided with parallel yoke arms between which is pivoted the eccentric jaw 13. This, as shown, is milled or roughened on the side adjacent the 70 block and is at all times held in position to engage the block by means of a spring 14, as shown in Figs. 1 and 3.

The operation is as follows: Having properly adjusted the eccentric jaw 13, with reference to the block 9, by means of the nut 11, the wire is drawn beneath said jaw in the position shown in Fig. 1, and the spring throwing the jaw into firm engagement therewith, clamps the same against the block. If now draft be applied to the device by means of the handle, the greater the tension upon the puller, the more firmly the jaw 13, engages the same upon the block. The milling on said jaw is exaggerated for purposes of illustration. In practice, the face of the jaw is merely sufficiently roughened to afford secure engagement with the wire. Should it be desired to use tackle in connection with the puller, it may be engaged either to the handle in any suitable manner, or the tackle may be engaged to the device through the aperture 5, in which event the draft is applied to the device at the most effective angle to assure efficient work. When operated manually, both hands may be employed, either on the handle or one at the handle and the other at the rear of the base plate. Of course, adjustment for varying 105 sizes of wire may be quickly effected by means of the nut 11. The angle of the

threaded shaft 12, with reference to the line of draft is such as to assure the most effective engagement with the wire.

Details of the construction may, of course, be varied without departing from the principles of this invention, and I therefore do not desire to limit the patent to be issued on this application otherwise than necessitated by the prior art.

10 I claim as my invention:

1. A wire puller of the class described embracing a base plate, a notched flange on the opposite sides of the rear end of said base plate, a tapered neck integral with the front end of said base, a handle integral with the end of said neck, a flange on the opposite sides of the inner end of said neck, a shoulder on said base plate, a longitudinally adjustable

bar on said base plate, a yoke on the lower end thereof, and a spring pressed eccentric jaw pivotally engaged in said yoke and acting to normally bear against said shoulder.

2. In a device of the class described a base plate, a flange on the opposite sides of the rear end of said base plate, a tapered neck integral with the front end of said base, a handle integral with the end of said neck and a flange on the opposite sides of the inner end of said neck.

In testimony whereof I have hereunto 30 subscribed my name in the presence of two subscribing witnesses.

DELAVAN W. HOUSE.
